UNITED STATES PATENT OFFICE.

ERNEST UNGER, OF NEW YORK, N. Y.

HAIR-WAVING HEATER.

Application filed August 26, 1922. Serial No. 584,447.

To all whom it may concern:

Be it known that I, ERNEST UNGER, a citizen of the United States, and resident of New York city, in the county of New York and State of New York, have invented certain new and useful Improvements in Hair-Waving Heaters, of which the following is a specification.

The invention relates to an electrically energized tubular heating unit for waving strands of hair on a person's head and the invention specifically relates to a metal blank from which the frame of such unit is formed.

In previously known forms of these heaters difficulty has been experienced in avoiding the objection that they were cumbersome and that their complicated construction to attain the degree of heat and the necessary heat insulation rendered them expensive as well as bulky. Further it is vitally necessary in the art of waving hair that a large number of these heaters be in use at one time. Therefore any heater unit having a structure or configuration which would tend to minimize the number of heaters which should be accommodated on the head, counts against the efficiency and thus minimizes the commercial value of such articles.

Accordingly, the primary object of the invention is to provide a simplified, easily constructed heater unit of the type outlined, which will feature minimum size, the concentration of a relatively high temperature within a small space adjacent the person's head and which at the same time can be readily handled while hot.

For the purpose of manipulating the units it has been found necessary in such articles to provide the same with an insulating handle which obviously adds to the cost, weight and bulkiness. This handle has heretofore been in the form of a relatively large member and has necessarily been of some bulk to provide the necessary securing means to the electric cable in those cases where the cable is passed through the handle.

The present disclosure features the use of part of the electric cable as a handle but instead of using a bulky, strain resistant member, the portion of the cable adjacent the unit is simply wrapped with asbestos cord and the cable firmly secured to the heater by means of a light metal

clamp which acts to transfer pulling strains from the handle or cable directly to the metal portion of the heater and relieves strain from the connection between the usual heating coil in such heater units and the electric conductors contained in the cable.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawing:

Figure 1 is a plan view of the metal blank from which the tubular frame of the heater is constructed;

Figure 2 is a perspective view of a heater constituting a preferred embodiment of the invention and with parts broken away to show internal construction;

Figure 3 is a longitudinal sectional view taken axially of the heater shown in Figure 2; and

Figure 4 is a transverse sectional view taken on the line 4—4 of Figure 3.

In the following description and in the claims, parts will be identified by specific names for convenience of expression but they are intended to be as generic in their application to similar parts as the art will permit.

Referring to the metal blank in Figure 1 there is shown a single piece of thin sheet brass; having a rectangular body portion 10 from one of the relatively long edges 11 of which extends a projection 12 substantially rectangular in plan and connected to the body portion 10 by means of a constricted neck portion 13. It is understood that the body portion 10 is bent about a cylindrical form until the edges 14 and 15 meet and are brazed together to form a relatively short open ended tube 16 adapted to contain all or a portion of the wrapped hair as is usual in the practicing of permanent hair waving such as is described in the patent to Kremer, No. 1,164,102.

The edges 17 and 18 of the extension are similarly brought together to form a tubular clamp 19 for containing the cable 20 hereinafter referred to. Opposite ends of

the tube 16 are provided with outstanding flanges 21 for confining the asbestos cement hereinafter described.

The tube 16 is wrapped with a layer of insulating material, such as mica, shown at 22 and this in turn is wrapped with a coil of heating wire 23 all as is usual in similar constructions now known. The wire is wrapped with a layer of asbestos cord 24 and this in turn is embedded in a layer of insulating cement 25 preferably of a character of cement which becomes hard when baked and which will form the outer protected surface to the heater. The cable 20 for supplying electric current to the heater is passed through the clamp 19 which has its free edges 17, 18 pressed into the cable so as to securely fasten the same to the tube 16. In this way any pull on the cable is transferred directly to the tube 16. The cable is provided with conductors 27 which are connected electrically to the free end of the heating wire 23 by spot welding 28. By this construction it is noted that the conductors in the cable are securely attached to the coil of heating wire wrapped about the tube 16 and the connections at 28 are free of any strains incidental to a pull on the cable. The cable is wrapped with asbestos cord 29 constituting an extension of the wrappings 24 and extends from the connection of the cable conductors with the heating wire for two or three inches along the length of the cable so as to provide an insulating handle 30.

It was noted from Figure 3 that the handle is offset from the tubular part adapted to contain the hair for a relatively short distance and in this way a plurality of these heaters may be assembled on the head with any desired spacing and even with the cylindrical body portions thereof touching each other. As so constructed the heater unit is formed simply of a single sheet of metal, a sheet of mica, a wrapping of heating wire and a coating of cement, it being obvious that the refinement of adding the wrapping of asbestos cord may be eliminated. However, it is found advisable to utilize the cord for it gives tensile strength to the cement; it minimizes any possibility of cracking and is relatively inexpensive. The sheet metal brass herein disclosed in Figure 1 may be of thinner gauge than has been used heretofore, dependence being placed upon the baked cementitious coating and the flanged ends of the tube to eliminate any tendency to distortion under strain.

With the device disclosed there is no need for providing means for repairing the same for it is cheaper to cut off the cable and throw a damaged heater away rather than make any attempt to repair the same. The heat may be concentrated as desired in the end of the tube designed to be positioned

adjacent the head simply by confining the wrappings of the heating wire adjacent the flange 21 opposite the clamp 19 in which case the portion of the tube adjacent the opposite end, that is the upper end of the showing in Figure 3, is free of heating wires.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. A blank for use in forming an electric heater for waving hair, said blank being a one-piece sheet of metal with a rectangular body portion having an extension from one edge thereof, said body portion designed to be bent into an open ended tube adapted to have a coil of heating wire wrapped about the same, the edges of the body portion which extend at right angles to the edge provided with the extension contacting to complete the tube and opposite edges of said extension adapted to be bent towards each other to form a tubular clamp for securing therein a cable leading to the heating wire.

2. In a device of the class described, the combination of a heater including a metal tube adapted to contain a strand of hair, a coil of heating wire wrapped about the tube, a cable leading to the heater and containing wires connected electrically to the heating wire, a layer of asbestos cable wrapped about the wire-wrapped tube and extended about a portion of the cable adjacent the heater to provide a heat-insulating handle and a cementitious layer of insulating material constituting the outer covering of the cord-wrapped tube.

3. In a device of the class described, the combination of a heater including a metal tube adapted to contain a strand of hair, a coil of heating wire wrapped about the tube, a cable leading to the heater and containing wires connected electrically to the heating wire and a layer of asbestos cable wrapped about the wire-wrapped tube and extended about a portion of the cable adjacent the heater to provide a heat-insulating handle.

4. A heating unit for waving hair including a tubular metal shell, a layer of insulating material surrounding the shell, a coil of heating wire wrapped about the insulating material, a cable for supplying current to the unit, said cable containing a pair of wires permanently connected to opposite ends of the coil of heating wire and a clamp secured to the shell and secured to the cable thereby to suspend the unit from the cable,

said clamp acting to prevent strains on the connection of the cable wires with the coiled heating wire.

5. In a device of the class described, the combination of a metal tube provided with integral outstanding flanges at opposite ends, a coil of heating wire wrapped about the tube and an outer coating of baked insulating cement enclosing the wires and contained between the flanges.

6. A heating unit comprising an open end metal tube, a layer of insulating material about the tube, a coil of heating wire wrapped about the insulating material, a wrapping of asbestos cord about the wire and an outer coating baked insulating cement embedding the cord wrapping.

7. A heating unit including a metallic tubular shell having a tubular extension from one end thereof, a coil of heating wire wrapped about the shell, a cable secured in said metallic tubular extension and containing electric conducting wires leading to opposite ends of the heating wire.

8. A heater for curling hair including a metal tube having an uninterrupted bore from end to end, a heating coil encircling the tube, an electric cable including conductors leading to said coil and a clamp for securing the cable to the tube.

Signed at New York city, in the county of New York and State of New York, this 21st day of Aug., A. D. 1922.

ERNEST UNGER.
